United States Patent Office.

ANTHONY ISKE, OF LANCASTER, PENNSYLVANIA.

Letters Patent No. 64,109, dated April 23, 1867.

IMPROVED SASH-ROPE PLATE.

The Schedule referred to in these Letters Patent and making part of the same.

TO ALL WHOM IT MAY CONCERN:

Be it known that I, ANTHONY ISKE, of Lancaster, in the county of Lancaster, and State of Pennsylvania, have invented a new and additional improvement to my Improvement in Window Sash, Patent No. 61,433, which consists in a design and construction of a metallic plate especially adapted thereto; and I do hereby declare that the following is a full and exact description thereof, reference being had to the accompanying drawings, making a part of this specification, in which—

Figures 1, 2, and 3 illustrate the construction and application of the knotted cord.

The object of this invention is to obviate the necessity of applying my extra strip to both sides of the sash, thereby greatly simplifying my former invention, being the same plate sent to the office prior to action being had on said patent, but not then admitted from a want of regularity in its presentation. This plate is so clearly shown in the drawings that any one skilled in the art can make and apply the same.

The oblong square plate A has a circular opening, B, through which the knot K on the end of the cord R is thrust, there being an excavation made in the sash, behind the plate, to allow the knot to slip upwards on the inclined sides E of the upper grooved portion D, raised or convex on the back portion of the plate; the cord entering the slot C above the opening B, and is thus buttoned, as it were, to the plate, there being a deep groove on the upper portion of the plate on its outer face in which the cord lies, a similar groove being continued in the wood of the sash for the cord leading to the pulley, as is usually the case in sash having cords and pulleys. This plate may also be used on each side of the sash for affixing the cords, instead of nailing, and answers far better than a cylindrical ring, in combination with an opening, neck and eye, or other similar appliances, where the knot is not hidden fully behind the plate and perfectly out of the way of friction.

I am aware that metal fixtures or sash-cord fasteners are not new for receiving and holding securely the knotted end of the rope or cord, at the same time admitting of its being readily cast off in removing the sash, such, for instance, as Patent No. 23,699. I disclaim a cylindrical ring or plate with outside fixings or elevated or depressed portions, other than the groove and countersunk screw holes, being more particularly desirous to use said plate A, when made in the manner shown, in combination with my extra strip, as specified and claimed in my patent aforesaid, No. 61,433, to which I offer this as an improvement, and therefore confine myself to its specific construction.

What I claim as my invention, and desire to secure by Letters Patent, is—

The specific arrangement of the plate A with its circular opening B, slot C, groove D, and bevelled convexity E on the back, all arranged in the manner and for the purpose specified.

ANTHONY ISKE.
